UNITED STATES PATENT OFFICE.

ROY B. AMBROSE AND JOHN W. PATTERSON, OF PITTSBURGH, PENNSYLVANIA.

FLUID METER.

Application filed June 4, 1925. Serial No. 34,858.

The present invention is an improvement in means for measuring the flow of fluids, as gasoline and the like, and for registering the amount used in operating a motor, preferably in connection with a mileage registering device.

Specifically, the device is designed to operate by intermittently operating mechanism, subject to actuation by one or a pair of rising and falling floats, located in a receiving and a discharging chamber respectively, and provided with circulation controlling valve mechanism, as hereinafter described. The invention also includes means for transmitting synchronized motion to a recording device, which is preferably located in comparative relation to a mileage gauge.

In the drawings showing one preferred embodiment of the invention:

20 Fig. 1 is a view of the device in elevation in position on the dashboard of an automobile.

Fig. 2 is an enlarged view in sectional elevation, showing the device with the valve 25 open, receiving fluid in the tank chamber and delivering to the carburetor chamber.

Fig. 3 is a similar view showing the reverse position, with valve closed, and the carburetor chamber full.

30 Fig. 4 is a vertical section on the line IV-IV of Fig. 2 with the valve open.

Fig. 5 is a plan view of Fig. 2, partly broken away.

Fig. 6 is a plan view of the trigger actuated valve mechanism, open as in the position of Fig. 2.

Fig. 7 is a similar view, showing the valve mechanism closed, as in Fig. 3.

40 Fig. 8 is a vertical sectional view of the mercury sealed transmitting gearing for the recording mechanism.

In general terms, the device constitutes a meter, utilizing a double chambered box 2, one chamber 3 being in receiving communication by connection 4 with a tank or other source of supply, the other chamber 5 being in delivering communication by connection 6, with a utilizing device, as a carburetor.

As shown, the chambers 3 and 5 are enclosed within a surrounding air tight casing 2 of cast or other suitable metal, with a dividing partition 7, extending to near the top cover 8, leaving a communicating air circulation space 9. Chamber 5, as shown, is somewhat deeper than chamber 3, providing capacity for gravity flow from the latter.

A further object is to always maintain the level in chamber 5 lower than in chamber 3, as well as to provide ample lower capacity in chamber 5.

60 The bottom portion of chamber 3 opens into chamber 5 through a valve-controlled port 10 which is opened and closed by a valve 11 of any suitable design. Said valve is designed to be actuated in conformity 65 with the operation of a pair of co-acting floats 12 and 13 in chambers 3 and 5 respectively, to deliver a measured amount of fluid to chamber 5 at each cycle operation of the floats.

70 For such purpose the floats are fixedly connected together by a tilting frame consisting of a pair of thin plates 14, 14, one at each side of partition 7, and fixedly connected with a common rock shaft 15. The 75 plates 14 are also connected above partition 7 by a stud or pin 16 adapted to freely ride back and forth along the air space clearance 9, as the float frame tilts towards one end or the other.

80 Valve 11 is opened and closed by mechanism actuated by the tilting frame and floats, adapted to quickly open or close the valve during their comparatively slow tilting movement. For such purpose we provide a 85 bell crank lever 17 pivoted at 18 to the bottom 19 of chamber 3, the short arm of the lever being connected at 20 with the valve by a stem 21. The long arm of the lever is connected at 22 with a spring 23 secured at 90 its other end to the terminal of a downwardly extending arm 24. Said arm is fixedly attached to rock shaft 15 of the float frame, and swings back and forth with each 95 tilting motion thereof.

95 With arm 24 in one tilted position, its terminal is at one side of the pivot or dead center 18, and in the other tilted position it is at the other side thereof. As arm 24 is moved by the tilting frame it thus effects 100 a sudden shifting of the lever, with accompanying opening or closing of valve 11, due to the tension of spring 23 at one side or the other of the dead center, as will be readily understood. Motion of lever 17 will be limited at one side or the other by the closing 105 of the valve 11 or by abutment stop 42, as in Figs. 7 and 6.

110 Thus with the floats in the position of Fig. 2 delivery chamber 5 has been drained down to the level where it is desirable to replenish it from chamber 3, float 13 having been

lowered as shown. Chamber 3 being constantly under the head pressure of supply conduit 4, previous to opening a valve 11, the tilting operation is assisted by upward flotation of float 12. Due to the fact that the double chamber interior of the casing is closed air tight, the pressure in each chamber will be always equal, by the communicating passage 9. Also, the contained air will always be somewhat compressed with a resulting reaction against the fluid, due to the constant supply connection to chamber 3.

Under such conditions, with valve 11 open, the delivery chamber 5 will be replenished until the fluid rises to the level, whereupon float 13 will rise and float 12 will fall, as in Fig. 3. During the accompanying reverse tilting of the frame, arm 24 will shift in a reverse direction past dead center 18 and close valve 11, as in Fig. 7.

Chamber 3 will again be refilled up to the limit of the air cushion resistance, during which time, or until emptied of the amount between high and low levels, fluid may be withdrawn from chamber 5, as to the carburetor of a gas engine.

Valve controlled port 10 is preferably of sufficient area to give a free discharge of fluid from chamber 3, into delivery chamber 5 at all times, so as to ensure prompt action of the valve after a short open period. Thus when the valve is opened by tilting of the frame, fluid will rise in chamber 3 only to a height where the float 12 will again tilt the frame, and cut off the feed from chamber 3. In this manner, the high level of fluid in chamber 5 is maintained always normally below that in chamber 3.

For the purpose of making an accumulating record of the quantity of fluid passing through the meter, we provide at any suitable point, preferably on the dash board, a registering device or dial recorder 25. Such device is also preferably located in visible comparative relation to the usual mileage indicating speedometer 26, so that comparison may be readily made at any time therewith to find the mileage-gallons consumed.

Recorder 25 is actuated through a flexible driving connection 27 with an actuating element in synchronized operative relation and connection with the tilting frame 14. For such transmission, we utilize a pawl 44 of lever 28, said pawl engaging ratchet wheel 29 on the upper end of a driving shaft or stem 30. Said stem is provided with a pinion 31, in driving engagement with a similar gear 32 on the lower end of a stem 33, which is in driving connection at 46 with flexible shafting 27.

Lever 28 is flexibly connected by link 34 with the end of frame stud 16, whereby reciprocation of the frame will thus transmit an accumulating intermittent movement to gears 31 and 32 and shafting 27.

By reason of the ratchet and pawl actuating mechanism being contained within the air tight chamber 5, the driving connection above described is necessarily effected through means sealing the same from the subsequent driving connections. For such purpose we utilize the shaft housings 35, 36, one inside chamber 5, the other outside, while the gears 31, 32, are likewise sealed within a surrounding fluid-tight casing 37, 38, held against the bottom of the casing in any suitable way.

The housings 35, 36, are fixedly located in operative relation to the casing and their lower portions and the interior of gear casings 37, 38, are provided with continuous clearance space sufficient to admit of a limited quantity of a suitable fluid sealing element, as mercury 39. As shown, there is an upwardly extending clearance opening 45 above the normal level of the mercury content 39, which is sufficiently large to receive and retain any surplus under various conditions or in different positions. The device may, therefore, be safely reversed, as in shipment, without impairment, the mercury resuming its normal relation when the sealing members are erected.

Stems 30 and 33 are mounted for free rotation in tubular bearing extensions 40, 40, and the stems are stepped in terminal bearings 41 for maintaining their continuous operative relation, as in Fig. 8. By such construction, the motion of the tilting frame will be transmitted to the outer recording device 25 with a minimum of friction and complete sealing against escape of air from the float chambers.

A pet cock 43 is located at a suitable or any desired level as shown, for the purpose of relieving or adjusting the air pressure if necessary, or for increasing the air pressure according to conditions. Such pet cock may be used to adjust the air volume and reacting pressure to the desired extent in connection with the desired level of fluid in chamber 5. When the machine is adjusted properly, the cock may be permanently closed.

The construction and operation of the invention will be readily understood from the foregoing description. Assuming the chambers 3 and 5 to be empty of fluid, containing air at say atmospheric pressure, inflow of liquid, as gasoline, through conduit 4 will elevate float 12, if valve 11 is closed, or will fill chamber 5 to the desired level if the valve is open. Thereupon float 13 will rise, closing the valve, and will then gradually lower as the supply in chamber 5 is drawn off down to the level where tilting of the frame will again open the valve.

In the meantime, a fresh volume of fluid will accumulate in chamber 3 for again filling chamber 5, such operation continuing as the fluid is used.

With each tilting operation a definite measured amount will be charged into chamber 5, filling it from the low level to high level, such amount constituting the measured unit represented by movement of the pawl and ratchet mechanism. The record indicating device 25 and the transmitting mechanism thereto will, of course, be properly designed and proportioned so as to indicate 10 the total unitary result of all fluid passing through the meter, as in gallons. The recording or total indicating mechanism may be of any suitable construction, and may of course, be actuated by electrically operated 15 means, if preferred.

It will be understood that the device may be changed or varied in detail construction, proportions, capacity, etc., by the skilled 20 mechanic, but all such changes are to be understood as within the scope of the following claims.

What we claim is:

1. A fluid meter consisting of a double chambered casing having a common upper 25 air space and providing a receiving and a distributing cavity with an intervening valve controlled port, a valve therefor, a tilting frame having an actuating float in one of said cavities, a pivoted lever connected with 30 the valve, an arm on the tilting frame, and a spring connecting the arm with said lever.

2. A fluid meter consisting of a double sided casing having a common upper air space and providing a receiving and a distributing chamber with supply and discharge 35 connections respectively, there being a valve controlled port connecting said chambers with each other, a valve therefor, a tilting frame having a float in each chamber, and quick-acting opening and closing 40 mechanism connecting the tilting frame and valve.

3. A fluid meter consisting of a double sided casing having a common upper air 45 space and providing a receiving and a distributing chamber with supply and discharge connections respectively, there being a valve controlled port connecting said chambers with each other, a valve therefor, 50 a tilting frame having a float in each chamber, a pivoted lever connected with the valve, and a spring connecting the lever with the tilting frame and movable across the lever pivot as the frame tilts.

4. A fluid meter consisting of a double 55 sided casing having a common upper air space and providing a receiving chamber at one side having a supply conduit, a distributing chamber at the other side extending below the receiving chamber and having a delivery conduit, a partition between said chambers having a valve controlled port, a valve therefor, a pivoted tilting frame having a float in each chamber and a downwardly extending arm, a pivoted lever connected with the valve, and a spring connecting the lever with the arm of the tilting frame adapted to quickly actuate the lever and valve when swinging across the lever pivot upon tilting of the frame in either direction. 60

5. In combination with a closed chamber meter of the class described having a float actuated tilting frame within the chamber, and an exterior totalizing indicating device, 65 an inner housing within the chamber, an outer housing exterior of the chamber, and connected motion transmitting mechanism in said housings in operative connection with the tilting frame and with the indicating device. 70

6. In combination with a closed chamber meter of the class described having a float actuated tilting frame within the chamber, and an exterior totalizing indicating device, an inner housing within the chamber, 75 an outer housing exterior of the chamber, a spindle within the inner housing having ratchet and pawl connection with the tilting frame, a spindle within the outer housing connected with the indicating device, and gearing connecting the spindles. 80

7. In combination with a closed chamber meter of the class described having a float actuated tilting frame within the chamber, and an exterior totalizing indicating device, 85 an inner housing within the chamber, an outer housing exterior of the chamber, a spindle within the inner housing having ratchet and pawl connection with the tilting frame, a spindle within the outer housing 90 connected with the indicating device, gearing connecting the spindles, a housing for said gearing, and a fluid sealing element within said housings. 95

In testimony whereof we hereunto affix our 105 signatures.

ROY B. AMBROSE.
JOHN W. PATTERSON.
